TUB GRAB BAR

Stanley R. Du Brie, Detroit, Mich.

Application June 23, 1953, Serial No. 25,619

Term of patent 14 years

(Cl. D4—3)

To all whom it may concern:

Be it known that I, Stanley R. Du Brie, a citizen of the United States, residing at Detroit, in the county of Wayne and State of Michigan, have invented a new, original, and ornamental Design for a Tub Grab Bar, of which the following is a specification, reference being had to the accompanying drawing, forming part hereof, in which:

The fragmentary disclosure of a tub in dotted lines is shown only for the purpose of illustration.

I claim:

The ornamental design for a tub grab bar, substantially as shown and described.
